[57] CLAIM

The ornamental design for an automatic fluid dispenser module for hot melt adhesive or the like, as shown and described.

DESCRIPTION

FIG. 1 is a side view of the automatic fluid dispenser module for hot melt adhesive or the like showing our new design;

FIG. 2 is a front view thereof;

FIG. 3 is a side view taken from the right of FIG. 2 of the side opposite that shown in FIG. 1;

FIG. 4 is a rear view thereof;

FIG. 5 is a top view thereof;

FIG. 6 is a bottom view thereof.

FIG. 3

FIG. 2

FIG. 1

FIG. 4

FIG. 5

FIG. 6
